UNITED STATES PATENT OFFICE.

CHARLES Y. KNIGHT, OF PASADENA, CALIFORNIA, ASSIGNOR TO KNIGHT AMERICAN PATENTS COMPANY, OF CHICAGO, ILLINOIS, A CORPORATION OF DELAWARE.

PROPELLING MECHANISM FOR AEROPLANES AND THE LIKE.

Application filed October 17, 1918. Serial No. 258,525.

To all whom it may concern:

Be it known that I, CHARLES Y. KNIGHT, a citizen of the United States, and a resident of the city of Pasadena, in the county 5 of Los Angeles and State of California, have invented certain new and useful Improvements in Propelling Mechanism for Aeroplanes and the like, of which the following is a specification.

10 My invention relates to propelling mechanism particularly applicable to aeroplanes, and the like, and has for one of its objects the provision of a hollow shaft for carrying a propeller and driven by one or more motors, or power units.

Another object is the provision of a propeller shaft or other driven shaft having a plurality of driving units disposed around such shaft and connected with the latter in 20 such a manner that the motor units direct their power to the said shaft through a gear on the latter.

A further object is the provision of a 25 simple and efficient means for directing the shots from a gun through the axial center of an aeroplane propeller without having to time the shots.

A still further object is the provision of 30 a hollow propeller shaft which shall serve as a guide through which to discharge projectiles, giving a rotary motion to the latter during their passage thus obviating the necessity of providing curved rifling in the bore of the shaft.

35 Another object is the provision of a driving connection between the engine and propeller shaft which will minimize the transmission of engine vibrations to the propeller shaft.

40 Other objects will appear hereinafter.

A diagrammatic representation of my invention is illustrated in the accompanying drawing forming a part of this specification, and in which the figure is a fragmental side view of an aeroplane construction embodying my invention, and having portions cut away to expose underlying parts.

45 In using rapid fire guns on aeroplanes and the like, it is necessary to mount such guns in positions where shots therefrom will not pass through the paths of the propellers or else to time the firing of such guns so that the shots will pass between the propeller blades. In my proposed construction I mount the gun barrel in such a man-

ner that it may be rotated and fix the propeller on the gun barrel so that shots from such gun will not interfere with the rotation of the propeller.

Referring more particularly to the drawing, I have indicated, more or less diagrammatically, an engine frame or crank casing 5 in which is mounted a plurality of motor or engine shafts 6. I have shown two of such shafts but it will be understood that 60 as many as may be desired may be provided. It is also to be understood that each engine shaft 6 may be driven by one or more motors. In the drawing one cylinder 7 is shown in connection with each shaft 6, but 65 when multi-cylinder engines are to be used, the other cylinders would be disposed directly behind the one indicated. In each of the cylinders 7 I provide a piston 8 and connect with it a connecting rod 9 70 which also connects with a wrist pin 10 and the latter carried by a gear wheel 11 on a shaft 6.

The engines are so arranged with relation 75 to the propeller shaft that the connecting rods swing in a plane parallel to or coincident with a plane embracing the longitudinal axis of the crank shaft. By this means vibrations set up by the movement of the connecting rods travel in a plane at right 80 angles to that of the transverse vibrations communicated to the propeller shaft through the gears. Thus both sets of vibrations instead of tending to augment one another as they do in constructions in which 85 the connecting rods swing in the plane of rotation of the propeller shaft, tend to interfere with and destroy one another.

I have indicated each wheel 11 as having 90 gear teeth 12 on its periphery meshing with 95 a worm or other form of spiral gear 13 which is fixed on a shaft 14 which serves as the barrel for the gun. I have found that the spiral gear of which the worm is one type to be most effectual in dampening 100 or absorbing the transverse impact stresses or vibrations which are ordinarily communicated from the motor to the propeller shaft through the gearing. This is due to the fact that in the spiral gear several teeth 105 are always in engagement, which distributes the stress over a large mass and because the teeth slide along one another so that what would be an impact blow at one point between two teeth of a spur gear is in the 110

spiral gear spread over an appreciable surface. Some of the shock, too, is absorbed in sliding friction between the gear teeth. The gun barrel and shaft 14 are mounted 5 in suitable bearings 15 in the frame 5. I have indicated the bearings 15 as being of metal such as are usually made of babbitt, bronze or other anti-friction metal, but it will be understood that any other form of 10 bearing may be used when desired. The gear 13 is provided with hubs 16 which engage the bearings 15 in order to take the thrusts on the shaft or gun barrel 14. It will be understood, however, that any other 15 means for taking the thrusts of shaft 14 may be provided.

I have indicated the frame 5 as being mounted on angle bars 17. This holds the frame 5 against rotation and is simply used 20 to illustrate a construction in which the frame 5 is held against rotation while the shaft 14 is rotated. In some types of engines it may be desirable to make different arrangements from those just mentioned.

25 On the forward end of the propeller shaft and gun barrel 14 I fix a propeller 18 which may be of any conventional or preferred pattern and secured to the shaft 14 in any desirable manner.

30 At the inner end of the gun barrel or shaft 14, I have indicated a gun breech mechanism 19. In this construction, the gun breech is preferably held stationary so that the charges may be easily placed into 35 it in any conventional manner and so that in shooting such charges, the shots will be directed through the rotating barrel 14. The barrel 14 is preferably provided with rifles, not shown, which should be either 40 straight or curved in such a manner as to give the desired rotary speed to the shot. The direction of these rifles is determined by the speed of the propeller shaft or gun barrel 14 and the forward speed of the projectile discharged.

45 In an aeroplane equipped with my construction, such aeroplane is directed toward the desired target which enables the gun to shoot directly through the propeller without interfering with the latter in any manner, or without being timed to miss the blades thereof. My construction also has the advantage of applying power to different 50 portions of the driving gear 13, that is each engine shaft 6 has its power transmitted to a different portion of the gear 13 from the power from the other shaft 6. This enables lighter materials to be used than where all of the power is transmitted from one 55 driving shaft to a driven shaft, and also tends to equalize the strains on the frame and other parts of the mechanism.

60 While I have described my invention in more or less detail and as being embodied 65 in certain precise forms I do not desire or

intend it to be thereby limited, as on the contrary the invention contemplates broadly all proper changes as well as the omission of immaterial elements and the substitution of equivalents therefor as circumstances 70 may suggest or necessity render expedient.

I claim:

1. In a propeller-shaft gun assembly, a propeller shaft bored for the discharge of projectiles therethrough, an engine having 75 a piston arranged in operative relation to said shaft, a connecting rod actuated by said piston and swinging in substantially the plane of the longitudinal axis of the shaft, means co-operating with said connecting rod and shaft respectively to transmit rotary motion to the latter.

2. In a propelling device for aeroplanes, a propelling shaft having a passage therethrough for the discharge of projectiles, a 80 motor for operating said shaft, a drive shaft for said motor supported at right angles to the longitudinal axis of said propeller shaft, and a train of spiral gears connecting said drive shaft with said propeller shaft.

3. In a propelling device for aeroplanes, a propelling shaft having a passage therethrough for the discharge of projectiles, a motor for operating said shaft, a drive shaft for said motor supported at right angles to the longitudinal axis of said propeller shaft, and means for transmitting power from said 85 driving shaft to the propeller shaft.

4. In a device of the character described, an aeroplane propeller shaft, a motor for operating said shaft, a connecting rod for said motor arranged to swing in a plane parallel to and including the longitudinal axis of said propeller shaft, and means to transmit power from said connecting rod to 100 the propeller shaft.

5. In a device of the character described, an aeroplane propeller shaft, a motor for operating said shaft, a connecting rod for said motor arranged to swing in a plane parallel to and including the longitudinal axis of said propeller shaft, and a train of 105 spiral gears connecting said rod with said propeller shaft.

6. In combination, a propeller shaft, a plurality of motors arranged radially around said shaft for operating the same, a drive shaft for each motor, each of said drive shafts lying in a plane at substantial right angles to the propeller shaft, a spiral gear on each drive shaft, and a spiral gear on the propeller shaft engaging with said 110 drive shaft gears.

7. In combination, a propeller shaft having a passage therethrough for the discharge of projectiles, a plurality of motors arranged radially around said shaft for operating the same, a drive shaft for each motor, said drive shafts lying in a plane at substantially 115 right angles to the propeller shaft, a spiral gear on the propeller shaft engaging with said drive shaft gears.

gear on each drive shaft, and a spiral gear on the propeller shaft engaging with the drive shaft gears.

8. In a device of the class described, a propeller shaft having a bore therethrough for the discharge of projectiles, a plurality of motors arranged radially of said shaft, each motor having a connecting rod arranged to swing in substantially the plane 10 of the longitudinal axis of the propeller shaft, means actuated by said connecting rods to transmit motion to said propeller shaft.

9. In a device of the class described, a propeller shaft having a bore therethrough for the discharge of projectiles, a plurality of motors arranged radially of said shaft, each motor having a connecting rod arranged to swing in substantially the plane 20 of the longitudinal axis of the propeller shaft, a spiral gear on said propeller shaft, and gears actuated by said connecting rods in engagement with said spiral gear.

10. In a device of the class described, a propeller shaft, a plurality of cylinders arranged radially of said shaft, a piston provided with a connecting rod in each cylinder, said connecting rods being arranged to swing in substantially the plane of the lon-

gitudinal axis of the propeller shaft, a spiral gear on said propeller shaft, and gears actuated by said connecting rods in engagement with said spiral gear.

11. In a propeller shaft construction, a crank case having oppositely alined openings, a propeller shaft journaled in said openings, a cylinder mounted on said crank case, a piston in said cylinder provided with a connecting rod, a gear on the propeller shaft within the crank case in the plane of the axis of said cylinder, and transmission means between said connecting rod and gear.

12. In a propeller shaft construction, a crank case having oppositely alined openings, a propeller shaft journaled in said openings having a bore therethrough for the discharge of projectiles, a cylinder mounted on said crank case, a piston in said cylinder provided with a connecting rod, a gear on the propeller shaft within the crank case, in the plane of the axis of said cylinder, and transmission means between said connecting rod and gear.

In testimony whereof I have signed my name to this specification on this 14th day 55 of October, A. D. 1918.

CHARLES Y. KNIGHT.
